UNITED STATES PATENT OFFICE.

GEORGE P. ABORN, OF WARREN, MASSACHUSETTS, ASSIGNOR TO THE GEO. F. BLAKE MANUFACTURING COMPANY, OF NEW YORK, N. Y.

SINKING-PUMP.

SPECIFICATION forming part of Letters Patent No. 592,038, dated October 19, 1897.

Application filed August 10, 1896. Serial No. 602,284. (No model.)

To all whom it may concern:

Be it known that I, GEORGE P. ABORN, a citizen of the United States, residing at Warren, in the county of Worcester and State of Massachusetts, have invented an Improvement in Sinking-Pumps, of which the following is a specification.

In mining operations it is often necessary to sink a shaft of comparatively small diameter and this often extends to a great depth, and it is very difficult to get into this shaft a pump that is sufficiently small not to obstruct the shaft, and at the same time sufficiently powerful to eject the water.

The object of the present invention is to obtain a very powerful pump that occupies but little space in the diameter of the shaft, but is extended sufficiently vertically to obtain the power necessary for raising the water from the shaft.

With the aforesaid object in view the pump is made double-acting, and two steam-cylinders are connected up in line with each other and are direct-acting upon the plunger of the pump; and by using two or more steam-cylinders working in the same direction and upon the same piston-rod the necessary power can be obtained, although the cylinders may be of comparatively small diameter, and hence occupy but a small space in the shaft that is being sunk; and the steam-cylinders arranged as a tandem engine are provided with valves actuated by contact with the valve-stems of the pistons at the extreme top and bottom movements to regulate the action of the steam in moving the valve by a valve-moving piston. Hence the power of the engine can be exerted throughout the entire stroke in giving movement to the plunger of the pump and the direction of motion will be reversed at the ends of the stroke by the action of the steam without outside connections or levers that would be liable to injury as the pump might be lowered or raised in the shaft.

In the drawings, Figure 1 is a vertical section of the engine and pump. Fig. 2 is a front elevation, partly in section. Figs. 3 and 4 show the valve and valve-moving piston. Fig. 5 is a plan view of the engine, and Fig.

6 is a diagrammatic illustration of the ports and connections. Fig. 7 is an elevation of the steam-cylinders with steam-chest cover, valve, and valve-moving piston removed; and Fig. 8 is a horizontal section in larger size at 55 x x, Fig. 1.

The pump is made of the cylinders A and A', connected together by the pipes and flanges B B', forming the waterways, and the plunger C is cylindrical and passes into both of the 60 cylinders, and there are packing-boxes or glands at D that make tight connections between the cylinders and the plunger but allow the plunger to work freely as it is reciprocated within the two cylinders.

The bottom head E of the cylinder A is preferably plain, and the head E' of the cylinder A' is provided with a gland or packing-box F, through which passes the piston-rod G, and the same is permanently connected to 70 the plunger C and extends into the steam-cylinders hereinafter described, and by this rod the plunger is reciprocated.

The valve-chest H is provided with inlet-valves 3 to admit the water from the induction-pipe I, and the valves 6 open into the chamber leading to the pipe B, and the pipe B' is connected to the induction-pipe I at its lower end and extends up to the valve-chest H', in which are the inlet-valves 5 and outlet-valves 7, and the pipe B joins with a pipe from above the valves 7 and continues as a rising discharge-pipe K.

The valves employed may be of any desired construction and the respective pipes B 85 and B' are to be sufficiently strong to properly connect the two cylinders A and A' and they may be provided with strengthening-flanges of any desired construction, and the movable covers to the valve-chests are shown 90 as vertical, but they may be arranged in any desired manner.

By the before-described construction the two cylinders can be permanently connected together and properly bored out in line with 95 each other and the glands or packings fitted in position so that the plunger will work without binding or undue friction, and the water will be forced out from the lower cylinder as the plunger descends, and forced out of the 100

upper cylinder as the plunger rises, so as to equalize the resistance to the reciprocation of the plunger.

The steam-cylinders L and M are preferably cast together and bored out in line with each other, and there is a packing-gland N between the two cylinders and around the piston-rod, and there are pistons O and O' in the respective cylinders and connected with the piston-rod G, and there are suitable columns or frame connections P between the head E' of the cylinder A' and the head Q of the cylinder M, so as to permanently connect the respective heads and retain the parts in line with each other.

The upper head R of the cylinder L is bolted in position, and there are projecting lugs on the cylinder and on the head receiving the bolts 8, to which the links 9 are connected and brought to a common ring for the purpose of suspending the sinking-pump and raising and lowering the same as required from time to time. The pistons O and O' occupy similar positions in the respective steam-cylinders and move together. Hence steam has to be simultaneously admitted upon the uppersides of the pistons when they reach the upper ends of the cylinders, and simultaneously admitted below the pistons when they reach the lower ends of the cylinders; and with this object in view the ports 10 and 11 are connected from the upper ends of the cylinders and the ports 12 and 13 from the lower ends of the cylinders, and these ports terminate at the valve-ports 14 and 15 respectively, and there is an intermediate exhaust-port 16 and the valve S is of ordinary character, usually a plain B slide-valve, and the parts are conveniently arranged so that the slide-valve S is moved transversely in admitting the steam to the respective ports, and with this object in view the valve-moving piston T is provided in the cylindrical ends of the steam-chest cover U, and steam is admitted by the pipe V into the steam-chest, and the valve-moving piston is made with a piston at each end in the cylindrical portion of the steam-chest cover, and there are horns or projections 17 on the valve entering a mortise in the middle portion of the valve-moving piston, so that the valve S will be moved by the action of steam upon the valve-moving piston T, such valve being moved transversely of the engine-cylinders.

At the top end of the cylinder L and the bottom end of the cylinder M there are valves 18 and 19, the stems of which pass through tubular guides and project into the cylinders, so that as the pistons complete the stroke downward the valve 19 will be opened, and as they complete the stroke upward the valve 18 will be opened. Each valve 18 or 19 is advantageously made cylindrical to slide in a cylindrical chest, and there is a spring 20 below the valve 19 to lift the same and cause it to seat itself upon an annular seat at the upper end of the valve-chamber as the piston rises, and the valve 18 usually will drop and

seat itself by gravity, and it is lifted by the upper piston as the piston completes its upward stroke. Pressure of the live steam tends to keep the valves 18 and 19 on their seats. There is a port 21 leading to the outer side of each piston-valve 18 and 19, so that the pressure of the live steam tends to keep the piston-valves upon their seats, and the ports 22 and 23 lead from the outer portions of the steam-chest cover U to the cylinders containing the valves 18 and 19, and such ports 22 and 23 open laterally through the cylinders for these valves 18 and 19, and the ends of 80 the ports are covered by the valves when such valves rest on their seats, and the ports 24 and 25 lead to the exhaust of the engine.

The operations of the parts are as follows: As the pistons are moved upward by the pressure of the steam the upper piston O' acts upon the stem of the valve 18 and lifts the same, and in so doing opens a communication from the port 22 to the exhaust-port 24, and the pressure of steam in the portion of the steam-chest outside one end of the valve-moving piston is relieved and the pressure of the steam moves such piston and the valve S to direct the steam-pressure upon the upper ends of the pistons O and O', and as these descend the valve 18 again returns to its seat and the steam-pressure at both ends of the valve-moving piston equalizes by the steam passing through small holes in the pistons, as seen in Figs. 4 and 8, and when the pistons approach the lower ends of the cylinders the piston O acts upon the stem of the valve 19, moving the same off its seat and opening a communication between the exhaust-port 25 and the port 23, leading to the opposite end of the valve-moving cylinder, so that the steam being exhausted therefrom the pressure causes the piston and valve to move in the opposite direction and again supply steam below the pistons and open the exhaust for the steam above the pistons. In this manner the tandem steam cylinder and pistons are moved to act directly upon the same piston-rod, and the valves 18 and 19, that are moved by the direct action of the piston at the respective ends of the strokes, direct the pressure of steam so as to move the valve-moving piston and valve and change the action of the steam upon the piston, and there is no risk of the ports becoming obstructed in their movements or for the steam-pistons to occupy a neutral position where the valves will not be moved, because the moment either of the valves 18 or 19 is acted upon the connections are made through the ports in such a manner that the exhaust is opened behind the valve-moving piston to insure a motion to such piston and to the valve by the pressure of the steam.

It is advantageous to provide a rock-shaft 26 to be moved by a hand-lever or wrench, and upon which rock-shaft a lever 27 is connected at the inner end to give motion to the valve-moving piston T, first in one direction and then in the other, in case such piston

should become rusted or otherwise obstructed in its movements.

In the plan view, Fig. 5, it will be seen that the parts are arranged compactly and so that but little space will be occupied by the pump and engine in the shaft, and I remark that this sinking-pump can be arranged for any desired depth of shaft by properly proportioning the size of the steam-cylinders to the size of the plunger, having reference to the pressure of steam made use of in the cylinders. This sinking-pump can be operated by air or other fluid under pressure, as well as by steam.

5 I claim as my invention—

1. The combination in a pumping-engine, of two pressure-cylinders in line with each other, two pistons in the cylinders and a piston-rod connecting such pistons, a double-acting pump and its plunger in line with and connected to the piston-rod, a valve and valve-seat and one port connecting to the upper ends of the two pressure-cylinders and another port connecting with the lower ends 5 of the two pressure-cylinders for admitting live fluid simultaneously to act upon the pistons in the same direction, and an exhaust-port for allowing the exhaust to pass from either the top or the bottom of the cylinders, a valve-moving piston and a cylinder containing the same, and an automatic mechanism for causing the pressure to move the piston and valve when the cylinder-pistons reach the upper and lower ends of their 5 strokes, substantially as set forth.

2. The combination in a pumping-engine, of two pressure-cylinders and an intermediate head in one casting, and packing in the head between the two cylinders for the piston-rod, two pistons and the connecting piston-rod within the cylinders, a pump-cylinder in line with the pressure-cylinders and rigidly

connected therewith, a plunger in the pump connected to the piston-rod of the steam-pistons, a valve at the upper end of the upper 45 pressure-cylinder and at the lower end of the lower pressure-cylinder, each valve being cylindrical and having a stem passing into the cylinder and acted upon by the piston, ports leading from the cylindrical cases of 50 the valves to the chest, a valve and valve-moving piston and pressure and exhaust ports, substantially as specified, whereby the valve-moving piston and valve are moved automatically by the pressure of the fluid, 55 the valves at the top and bottom ends of the pressure-cylinders regulating the exhaust from the outer ends of the cylinder containing the valve-moving piston, substantially as set forth.

3. The combination in a pumping-engine, of two pressure-cylinders in line with each other, two pistons in the cylinders and a piston-rod connecting such pistons, a double-acting pump and its plunger in line with and 65 connected to the piston-rod, a valve and valve-seat and one port connecting to the upper ends of the two pressure-cylinders, and another port connecting with the lower ends 70 of the two pressure-cylinders for admitting fluid simultaneously to act upon the pistons in either one direction or the other, and an exhaust-port for allowing the exhaust to pass from either the top or the bottom of the cylinders, and a valve-moving piston and valves 75 for the same acted upon by the pistons near the ends of the strokes, substantially as specified.

Signed by me this 1st day of August, 1896.

GEORGE P. ABORN.
